I. BERNSTEIN.
WORKING GARMENT,
FILED JUNE 23, 1920.

INVENTOR.
Isaac Bernstein,
BY *Chas. E. Grunwald*,
ATTORNEY

UNITED STATES PATENT OFFICE.

ISAAC BERNSTEIN, OF OAKLAND, CALIFORNIA.

WORKING GARMENT.

Application filed June 23, 1920. Serial No. 390,997.

To all whom it may concern:

Be it known that I, ISAAC BERNSTEIN, a citizen of the United States, residing at Oakland, in the county of Alameda and 5 State of California, have invented a new and useful Improvement in Working Garments, of which the following is a specification.

This invention relates to a garment and 10 particularly pertains to coveralls.

It is the principal object of the present invention to provide a garment in the nature of coveralls which embodies a pair of overalls and a jumper or jacket, the overalls and 15 jacket being so constructed as to neatly cover the clothes of the wearer and providing that the suit of coveralls may be entirely or partially removed without difficulty and further insuring that the coveralls may 20 be worn alone or the jacket worn alone if desired.

The present invention contemplates the use of a jacket having straps secured to the shoulders thereof to engage the bib of a 25 pair of overalls thereby eliminating the usual back straps, said jacket and overalls being connected across the back and along the waist by suitable fasteners which may be conveniently operated.

30 The invention is illustrated by way of example in the accompanying drawings in which:

Fig. 1 is a view in front elevation showing the complete garment.

35 Fig. 2 is a view in front elevation showing the garment with the bib unfastened and hanging down.

Fig. 3 is an enlarged fragmentary view showing the manner in which the jacket is 40 secured to the waist of the overalls.

Fig. 4 is an enlarged view in section through one of the fasteners as seen on the line 4—4 of Figure 3.

Fig. 5 is a view in section showing the 45 fastening of one of the shoulder straps as seen on the line 5—5 of Fig. 2 and indicating in dotted lines the manner in which the shoulder straps may be concealed.

Fig. 6 is a fragmentary view in elevation 50 showing the manner in which suspender straps are used with the overalls to eliminate the use of the jacket.

Referring more particularly to the drawings, 10 indicates a pair of overalls and 11

indicates a jacket or jumper. These two 55 articles of wearing apparel are intended to be used in conjunction with each other although they are so formed so as to be used separately as desired, for example, the overalls may be equipped with suspender straps 60 12 which would eliminate the use of the jacket and the jacket if desired may be arranged to conceal the shoulder straps 13 so that it may be used separately. The jacket may be formed with long sleeves or may be 65 in the shape of a vest and is here shown as having a neck band 14 opening at the front and secured by a fastener 15. The jacket is further opened completely down the front so that it may be readily removed and will 70 greatly resemble a vest in its construction. It is preferable that the front of the jacket be formed with panels 15' and 16 adapted to be fastened or buttoned together along the center of the jacket and stitched to a 75 back panel 17 along their outer edges. The lower line of the jacket terminates substantially along the waist line of the wearer and is there equipped with a plurality of fasteners 18. These fasteners as shown in Fig. 80 3 have a securing plate 19 carrying a pivoted hook member 20. The hook member is adapted to pass through eyelets 21 arranged along with back portion of the waist band of the overalls, the hooks after passing 85 through the eyelets being folded up in the position shown in Fig. 4 to secure the jacket and overalls together.

The shoulder seams of the jacket are made to receive the upper ends of the shoulder 90 straps 13. It is to be noted that the shoulder straps, are not, however, stitched to the front panels 15' and 16 of the jacket, thus providing an opening 22 in the seam through which the shoulder strap may extend as 95 shown in Fig. 2 or from which it may be withdrawn to assume the dotted line position as indicated in Fig. 5. This will permit the shoulder straps to be concealed within the garment when it is desired to use the 100 garment separately or when it is used with overalls other than the pair furnished therewith.

The overalls are substantially of common design having a bib 23 and the usual leg 105 members. The bib, of course, extends a considerable distance above the waist of the overalls in front terminating at the waist

line on the two sides of the garment. The leg members are split down the side seams for a distance below the waist line to permit access to the side pockets of the trousers worn by the wearer. The back of the overalls are formed with a waist band 24 along which the eyelets 21 are arranged and by which the waist band may be secured to the jacket by fasteners 18.

10 In using the garment a jacket may be placed on the wearer and buttoned down the front after which the overalls are put on. The bib of the overalls is secured over the front of the jacket by adjustable fastening members 25 engaging buttons 26 on the bib. The back of the overalls may then be secured to the back of the jacket by the fasteners 18. When this has been done a complete suit of coveralls will be formed, attention being directed to the fact that there are no back straps on the overalls which might become twisted or caught upon objects and that the shoulder straps merely hang from the shoulder seams of the jacket to be quickly and conveniently secured to the bib of the overalls. When it is desired to use the jacket separately the shoulder straps may be drawn through the openings 23 and concealed within the jacket. If the overalls are to be used 30 separately a pair of suspender straps 12 may be secured to the buttons 26 on the overall bib while hooks on the straps may engage the eyelets 21 in the back of the overalls.

It will thus be seen that a working garment is here provided adapted to be easily put on and taken off either in one or two pieces and that the separate parts of the garment may be worn independently if desired.

40 While I have shown the preferred form of my invention as now known to me it will be understood that various changes in the construction, combination and arrangement of parts may be made by those skilled in the art without departing from the spirit of the invention as claimed.

Having thus described my invention, what

I claim and desire to secure by Letters Patent, is:

1. An exterior garment including leg inclosing members with a front upwardly extending bib, an open front jacket having shoulder seams, engaging means at the back of the waist line of both garment members and straps fixed within the shoulder seam of the jacket and extensible to connect with the bib and foldable through slots in the shoulder seams.

2. An exterior garment comprising trousers having a front upwardly extending bib and a plain rear waist line, an open front jacket, engaging means at the back of the waist line of both garment members, straps fixed at their upper ends within the shoulder portions of said jacket and of a length whereby they may be connected to the bib, said jacket having slots formed therein at the front thereof adjacent the shoulder portions through which said straps are insertable, whereby the bib may be optionally supported in a concealed position within the jacket or at the exterior thereof.

3. An exterior garment comprising trousers having a front upwardly extending bib and a plain rear waist line, an open front jacket member having shoulder seams, straps secured at their upper ends within the jacket at said seams and of a length whereby they may be connected to said bib, engaging means at the rear waist line of each garment member, said jacket member having slots formed in the front thereof adjacent the shoulder portions and through which said straps are insertable, whereby the bib and straps may be optionally disposed and connected within the jacket or disposed and connected exteriorly thereof.

In testimony whereof I have hereunto set my hand in the presence of two subscribing witnesses.

ISAAC BERNSTEIN.

Witnesses:

RALPH A. KNAPP,
AMELIA P. DA ROSA.
